CLAIM

The ornamental design for a container for drinking glasses, as shown and described.

DESCRIPTION

FIG. 1 is a top plan view of the lid portion of a container for drinking glasses where the side wall portion and base portion are removed for ease of illustration.

FIG. 2 is a bottom plan view thereof.

FIG. 3 is a side elevation view thereof.

FIG. 4 is a bottom plan view of the support portion of a container for drinking glasses where the top portion and side wall are removed for ease of illustration.

FIG. 5 is a top plan view thereof.

FIG. 6 is a side elevation view thereof.

FIG. 7 is a side elevation view of a container for drinking glasses where the top and base are connected by a side wall portion and all sides being the same; and,

FIG. 8 is an exploded perspective view thereof.
